UNITED STATES PATENT OFFICE.

JULES PUECH, OF PARIS, FRANCE.

PLOWING MACHINE.

Application filed December 29, 1920. Serial No. 483,882.

To all whom it may concern:

Be it known that I, JULES PUECH, a citizen of the Republic of France, residing in Paris, France, have invented new and useful Improvements in or Relating to Plowing Machines, of which the following is a specification.

This invention relates to plowing machines having means for raising the plow shares, and consists in a device for automatically raising the plow shares, said device comprising a rear wheel, mounted on a fork secured to a sleeve rotatable about a pin which oscillates about a transverse trunnion, the free end of the said pin being connected to one or more springs, the ends of which are secured to the seat.

A seat is mounted on a metal blade and connected by any suitable means to the said spring. The free end of the metal blade engages, under the action of the weight of the operator, with the fork of the wheel and locks the same in a fixed position, its travel being limited by the tension of the above mentioned spring or springs and by an adjustable stop.

A metal spindle terminates in a recessed box receiving the support of the seat, within which box moves the pin secured to the fork of the wheel. This arrangement enables the device to be secured to any plow or similar apparatus.

A construction according to the invention is illustrated merely by way of example in the accompanying drawing.

Figure 1 is a longitudinal elevation of the invention showing its application to a Brabant plow driven by a tractor fore-carriage.

Figure 2 is a modified construction according to the invention, comprising an additional raising device.

The hub 2 of the wheel 1 is secured to a fork 3 which is made integral with a sleeve 4 mounted at 5 on the lower part of a pin 7 and secured by means of a nut 6 or any other suitable device, the sleeve 4 being freely rotatable about the journal 5.

The pin 7 is provided with a lug 8 by means of which it is mounted on a horizontal trunnion 9 about which it pivots.

The upper end of the pin 7 is provided with a ring 10 with which engage the ends of the springs 11. The pin 7 and its collar 8 which are movable about the trunnion 9, move in the interior of a recessed box 12

connected to a rod 13. This rod passes through two sockets or sleeves 14 and 15 mounted on the beam 16 of the plow and is secured at its end 17 by means of any suitable device, key, bolt, etc.

The recessed box 12 is provided with a circular flange 32 with which the plow engages for working positions or for the position of returning on the road (horizontal 65 plow).

To the box 12 is secured a bent metal blade 18 on which is secured the seat 19 under which is arranged another rod 20 terminating in a handle.

To the blade 18 is riveted a metal blade 21, also bent, the upper end 22 of which has a hole intended to afford passage to a screw-threaded rod 23 on which is screwed a handle 24 forming a nut and enabling the tension of the springs to be adjusted by moving the said rod in the horizontal direction.

The end 25 of the rod 23 forms the point of attachment for the springs 11, the ends of which are secured to the ring 10 of the pin 7.

The lower end of the blade 21 terminates in a bent part 26 which engages between the prongs of the fork 3 and thus locks the wheel in the axis of the whole apparatus.

The whole of the device is secured to the plow 27 which in its turn is attached to the tractor fore-carriage 28 by means of a suitable coupling 20.

The working of the apparatus is as follows:—

The apparatus being on the road, with the plowman on the seat, the apparatus can be steered by means of the hand wheel 30, the shares 31 of the plow mounted on a frame, being held in a horizontal plane parallel to the road by means of a device not shown in the drawing.

When it is desired to turn on the spot, the attendant descends from his seat. The pin 7, under the action of the springs 11, pivots about the trunnion 9 and assumes vertical position and raises the shares of the plow. At this moment, the part 26 of the blade 21 becomes disengaged from the fork, and the wheel 1 can turn freely about the pin 7, and assume any possible positions about the said pin.

The attendant merely has to get hold of the back of his seat by the handle 20 and to steer it as required.

On arriving in the field, the attendant

places the tractor at a suitable point, turns the plow so as to place the shares 31 in the vertical plane, and sits on the seat. At that moment his weight lowers the plow and inclines the pin 7, the part 26 of the blade 21 locks the wheel 1 which consequently remains in the axis of the apparatus.

The plow then works with the shares penetrating the soil. At the end of the furrow, 10 the attendant descends from his seat, the result of which is that the pin 7 will be brought into a vertical position, the whole of the shares of the plow being raised, the attendant merely has to turn his tractor by 15 means of the handle 20, the wheel 1 being free to turn.

In a modified construction of the device the seat is fixed on a spindle which can oscillate in the interior of a box supported 20 by the frame of the apparatus; the upper end of the said spindle forming the point of attachment for one or two springs balancing the weight of the shares, and the bottom end of the said spindle locking the fork under the action of the weight of the attendant. The handle 24 is used for regulating the tension of the springs.

The device could be applied to any kind 30 of agricultural machine. In fact, the rod 13 could be separated from the body of the machine by removing the fixing device 17. It will be sufficient if the machine to which the device is to be fitted, has two sleeves such as 15 and 14 enabling the rod 13 to 35 be introduced and fixed.

In this case, the raising of the shares at the end of the field, will be produced automatically, before the stoppage, by the resistance of the soil, after the engaging gear 40 has been previously operated.

The fork 3 of the rear wheel is mounted on the sleeve 4 by means of a horizontal pin

33 enabling the shares of the plow to be raised to a greater extent by pressing on the pedal 34.

The device constitutes a simple and solid structure more particularly adapted for agricultural work, its working is easy, and the facility with which all the parts can be examined and kept in order are desirable qualities in agricultural machines which are usually entrusted to men more or less inexperienced. Moreover, the mobility of the apparatus, when the operator has vacated the seat, makes the turning of the whole 55 very easy, and this turning can be done on the spot whilst with the systems at present used, it is very frequently necessary to have recourse to long and tedious maneuvers, necessitating a large amount of space.

It will be obvious that the invention may be modified in various ways, without departing from the spirit of the invention.

Having now particularly described and ascertained the nature of my said invention 65 and in what manner the same is to be performed, I declare that what I claim is:—

In a plowing machine a beam, a support fixed thereto, a pin pivotally secured to the support for angular movement in a vertical 70 plane, a fork pivotally connected to said pin for lateral swinging movement, a wheel mounted in the fork, tensioning lifting springs connected to the upper portion of the pin and to the support, and means on the 75 support to lock the fork against pivotal movement when the support is lowered, together with the rear end of the beam, and to release the fork when the support and rear end of the beam are raised by the 80 springs.

In witness whereof I affix my signature.

JULES PUECH.
